UNITED STATES PATENT OFFICE

FRANK F. FISCHER, OF OMAHA, NEBRASKA

DESIGN FOR A MEMORIAL GRAVE MARKER

Application filed April 18, 1932. Serial No. 43,533. Term of patent 7 years.

To all whom it may concern:

Be it known that I, FRANK F. FISCHER, a citizen of the United States, residing at Omaha, in the county of Douglas and State of Nebraska, have invented a new, original, and ornamental Design for a Memorial Grave Marker, of which the following is a specification; reference being had to the accompanying drawing, forming a part thereof.

I claim:

The ornamental design for a memorial grave marker, as shown.

FRANK F. FISCHER.
